(57) CLAIM

The ornamental design for the ashtray, as shown and described.

DESCRIPTION

FIG. 1 is a top perspective view of the ashtray;

FIG. 2 is a right side plan view of the ashtray, the left side being identical;

FIG. 3 is a top plan view of the ashtray; and,

FIG. 4 is a front side plan view of the ashtray, the back side being identical.

The broken line environmental showing is for illustrative purposes only and forms no part of the claimed design.
